UNITED STATES PATENT OFFICE.

EDWIN M. ROSENBLUTH, OF PHILADELPHIA, PENNSYLVANIA.

DESIGN FOR A MEMBER FOR LAMP-BRACKETS.

SPECIFICATION forming part of Design No. 32,167, dated January 30, 1900.

Application filed July 3, 1899. Serial No. 722,767. Term of patent 7 years.

To all whom it may concern:

Be it known that I, EDWIN M. ROSENBLUTH, of Philadelphia, in the State of Pennsylvania, have invented and produced a new and useful Design for a Member of a Lamp-Bracket, whereof the following is a specification, reference being had to the accompanying drawings.

My invention is peculiarly applicable to a bracket arranged to be secured upon a vehicle-frame to support a lamp in detachable relation therewith.

The drawing shows a perspective view of a

bracket member A embodying my design, the material feature thereof consisting of a flattened portion B and a tubular extension thereof C.

Having described my invention, what I claim as new, and desire to secure by Letters Patent, is—

The design for a member of a lamp-bracket as herein shown and described.

EDWIN M. ROSENBLUTH.
